CHARLES NELSON, OF BROOKLYN, NEW YORK, ASSIGNOR TO S. STERNAU & COMPANY, A COPARTNERSHIP COMPOSED OF SIGMUND STERNAU AND LIONEL STRASSBURGER, OF BROOKLYN, NEW YORK.

VAPOR-LAMP.

1,099,192.

Specification of Letters Patent.

Patented June 9, 1914.

Application filed January 17, 1913. Serial No. 742,547.

To all whom it may concern:

Be it known that I, CHARLES NELSON, a citizen of the United States, residing in the borough of Brooklyn, county of Kings, city 5 and State of New York, have invented a certain new and useful Vapor-Lamp, of which the following is a specification.

This invention relates to lamps, for heating and other purposes, burning liquid fluid, 10 such as alcohol. The lamp is of the type in which the fluid is subjected to heat within a wick tube, to produce vapor, which is ignited in a burner.

The objects that I have in view are:—
15 First: to ease the pressure within the fluid font, caused by the generation of vapor. Second: to prevent injurious leakage of fluid through the vapor passage. Third: to simplify the burner and render it more 20 efficient. Fourth: to improve the means for supplying a primary charge of fluid to the wick tube. These and further objects will more fully appear from the following specification and accompanying drawings, considered together or separately.

In the drawings, Figure 1 is a vertical section of a lamp embodying my invention. Fig. 2 is a plan view of the same, and Fig. 3 is a sectional view taken on the line 3—3 of 30 Fig. 1.

In all of the views, like parts are designated by the same reference characters. The font 1, is shown as circular in plan. It is preferably made of sheet metal, so as 35 to be both liquid and vapor-tight. The liquid fuel is introduced through a filling opening which is normally closed by a suitable cap 2, which is shown as attached in place by means of screw threads. In the 40 center of the top of the font is a circular opening, surrounded by a collar 3. This collar is preferably provided with screw threads for attachment of the wick tube. The wick tube 4 is preferably made of sheet metal, and is constructed as follows:—The 45 top is closed, the upper portion of the tube being preferably of uniform diameter, as shown. The lower portion of the tube is formed with an enlargement 5, concentric 50 to the tube. At the bottom, the walls of the tube are doubled back, forming a sleeve 6 of greater diameter than the enlargement 5, said sleeve preferably having screw threads

at its upper part, for engagement with the threads upon the collar 3. The space between the enlargement 5 and the sleeve 6 55 constitutes an air jacket 7.

The wick tube may be removed from the font by rotating it, so that the threads on the sleeve 6 become disengaged from the threads on the collar 3. The parts are best proportioned so that when in position, the lower end of the tube is above the bottom of the font a sufficient distance to allow the fluid to circulate freely below the same. 60 The air jacket serves to insulate the wick tube from the font, and prevents the latter from becoming heated, with the consequent production of vapor under pressure in the font. It also allows the use of a relatively 65 large burner, made possible without unduly heating the font.

The tube 4 contains a wick 8. The upper portion of the wick is preferably made of asbestos, so as not to become charred when 70 subjected to the intense heat that the lamp undergoes when in use. The lower part of the wick is preferably made of cotton. I prefer to make this part of the wick as follows: A casing of woven cotton, of a sufficient length to reach from the bottom of the font to the asbestos, and of such size as to fit snugly within the smaller part of the tube, is filled with longitudinally arranged 75 strands of cotton, as shown. That part of the wick which lies within the enlargement 80 5 is wrapped with cotton strands as shown, so that its outside dimensions will be such that it will completely fill the enlargement. This wrapping will compress the lower part 85 of the casing, and also compress the lower portions of the center longitudinal strands. The effect of this structure will be that the lower part of the wick will be somewhat denser than the upper part, and the resistance 90 to the flow of fluid will be greater, so that the fluid will not be driven downward by the pressure of the vapor which is generated in the upper parts of the tube.

The means for withdrawing and burning 100 the vapor is as follows:—A vapor tube 9, shown as horizontal, extends from one side of the wick tube. This tube may be attached by having its end reduced and threaded, and a nut 10 applied to the threaded end. 105 The inner end of the interior of the tube is

reduced, as shown, upon inclined lines, so as to form a seat for a valve 11. The stem of the valve is screw-threaded, such threads engaging with threads in the vapor tube, so that the position of the valve may be adjusted, and the amount of vapor which flows to the burner regulated. A sharp instrument can be introduced through the vapor tube, into the asbestos part of the wick, so as to produce a passage for the vapor, and reduce the chance of particles of asbestos entering the vapor tube.

To the vapor tube 9 is attached an outlet tube 12. This tube is shown as vertical, closed at the top and provided with an outwardly directed orifice 13. The vapor passes out through this orifice, and enters the burner ring 14. This burner ring is made as follows: It is preferably made of sheet metal, as shown. A perforated plate 15 having in the center thereof an opening through which enters the top of the wick tube, partly supports the ring. The plate also contains an opening for the entrance of the upper end of the outlet tube 12. The ring proper is in the form of an annulus, with a curved outer side, and plane inner walls and plane bottom, as shown. In the inner wall is an opening 16, opposite to the orifice 13. In the same wall are orifices 17, which are shown as four in number. These direct the flame to the wick tube, and keep it hot. On the curved exterior of the annulus is a row of orifices 18, directed upward. These produce the flame for the greater proportion of the heating effect of the lamp. Some of the flame from vapor issuing through the orifices 17 will pass through the perforations in the plate 15, and will add to the heating effect. The ring 14 is further supported by means of a cage 19, which surrounds and is supported by the wick tube. I prefer to attach the ring 14 to the cage 19, by providing the latter with a plurality of lips 23, which are bent over the outer edge of the ring and hold it in place.

The wick tube is shown as having a shallow flange at the middle, for aiding in the support of the cage. The bottom of the cage is formed into a pan 20, concentric to the wick tube. The pan is for the purpose of containing fuel, which, upon being burnt, will heat the upper part of the wick tube, and this generates vapor so that the lamp may be started.

In operation, after the tube has become hot, the fluid contained in the asbestos portion of the wick will become vaporized, and will escape through the vapor tube 9 and enter the outlet tube 12, to an extent which will depend upon the amount of opening of the valve 11. The vapor will escape through the orifice 13, and will enter the ring 14, the flame escaping through the 65 orifices 17 and 18.

It is found in practice that some liquid fuel will enter the vapor tube 9, and will be ejected through the orifice 13, during the starting of the lamp, when liquid is burning in the pan. If no provision be made to guard against injury, this liquid will flow downward on the outside of the tubes 12 and 9, and will pass along the tube 9, and the valve stem 11, finally dropping off upon the top of the font, and thence to the support of the latter. The fluid may become ignited, and may cause injury as well as being objectionable. To avoid this trouble, I provide the following device: The outer end of the tube 9 is provided with a sleeve 21, close to the end of the tube. To this sleeve is connected a trough 22, which is inclined as shown, and with its lower end over the pan 20. I may conveniently make the sleeve and trough of a single piece of sheet metal. The effect of this structure is that the fluid, when it traverses the outside of the tube 9, upon reaching the sleeve 21, its horizontal travel will be arrested, and it will then drop to the trough and, running down the latter, will enter the pan and be consumed, without injury or danger.

The liquid fuel is introduced into the pan 20 by any suitable means, but preferably by means of the pump illustrated. This pump 95 comprises a cylinder 24, closed at the top with a plug 25. This plug is quite thick, as shown, and has a concentric inset portion, for entrance of the upper edge of the flange of the piston 26. This latter is preferably made of the shape shown, and has a plurality of ports. A disk valve 27 lies upon the piston and is adapted to cover and uncover the ports. A piston rod 28 is attached to the piston and extends through the plug 25. An inlet port 29 is provided at the lower end of the cylinder 24, and a spring 30 lies within the cylinder and exerts pressure upward, so that the piston is normally held in the position shown in the drawings. The plug 25 is connected to a tube 31, which makes a tight fit with a sleeve 32, carried by the cap 2. This tube is connected to and supports a spout 33, which has a discharge end immediately over the pan 20. The lower end of the cylinder 24 is preferably very close to the bottom of the font, so that the pump will work when the latter is nearly empty. In operation, the rod 28 is depressed a few times, which forces the piston downward allowing fluid to pass through the ports in the piston. Upon the spring 30 being allowed to elevate the piston, the valve will close and the fluid will pass upward through the tube 31, and spout 33, and into the pan 20.

The excess of vapor in the font escapes through a vent 34 in the filling cap 2. I regard the feature of supporting the pump upon the cap as important, as the pump may be removed for inspection or adjustment 130

very readily, and only one opening in the top of the font is needed, for both the filling cap and pump.

In accordance with the provisions of the patent statutes, I have described the principle of my invention, together with the apparatus which I now consider to represent the best embodiment thereof; but I desire to have it understood that the apparatus shown is merely illustrative and that the invention may be carried out in other ways.

Having now described my invention, what I claim as new and desire to secure by Letters Patent, is:—

1. A vapor lamp having a wick tube with an enlargement at the lower end, with a wick, said wick being formed of a casing, a filling and an outside layer wrapped around

the lower part of the casing and occupying the enlargement.

20

2. A vapor lamp having a wick tube, a vapor tube extending out from one side thereof, with a valve within the said vapor tube, a vertical outlet tube extending upward and outside of the wick tube, said outlet tube having an orifice directed outward, and a burner ring outside of said wick tube, and with an opening therein opposite to said orifice.
